UNITED STATES PATENT OFFICE.

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING-MACHINE.

1,392,596.

Specification of Letters Patent.

Patented Oct. 4, 1921.

Application filed January 30, 1920. Serial No. 355,094.

To all whom it may concern:

Be it known that I, EUGENE J. RAY, a citizen of the United States, residing at Beverly, in the county of Essex and State 5 of Massachusetts, have invented certain new and useful Improvements in Skiving-Machines; and I do hereby declare the following to be a full, clear, and exact description of the invention, such as will enable others 10 skilled in the art to which it appertains to make and use the same.

The invention relates to skiving machines, and more particularly to machines of this character which comprise a rotary tubular 15 skiving knife, a presser foot, and a feed roll, arranged to coöperate with the presser foot in positioning the material to be operated upon, and feeding it against the knife.

The object of the invention is to so moisten 20 the knife of a machine of this character that it will operate successfully upon rubber, rubber stock or similar plastic or semi-plastic material. To this end means is provided for applying a thin film of moisture to the 25 knife at its edge and for such distance back from its edge so that there will be no adhesion of the stock to the periphery of the knife as it passes from under the presser foot at the point of operation of the knife. 30 The means which is preferably utilized for supplying the moisture so that it will be evenly and uniformly distributed over the requisite surface both within and without the knife edge, and in such quantities that 35 it will not be thrown off to an objectionable extent by centrifugal force, comprises a spring operated carrier adapted to present a moistening pad to the edge and outer surface of the knife and to press it continuously 40 against the periphery of the knife.

It has been found that a moistening pad 45 consisting of sponge is peculiarly adapted for properly moistening the knife of a skiving machine which is to operate on rubber stock, and such a pad is, therefore, utilized. Water may be supplied to the sponge pad in suitable quantities by a pipe from which the water drips onto the pad, and in such case uniform drip of the water may be secured by plugging the end of the pipe with 50 sponge.

A preferred form of the invention is 55 shown in the drawings, in which Figure 1 is a front elevation showing so much of a skiving machine as is necessary to illustrate

the application of the present invention thereto. Fig. 2 is a side elevation and Fig. 3 is a detail section view on line 3, 3, Fig. 1.

In the drawings the invention is shown 60 applied to a skiving machine similar in construction and mode of operation to the machine shown and described in Patent No. 1,301,283, April 22, 1919. This machine is provided with a rotary tubular knife 2, a 65 yielding feed roll 4 and with a presser foot which is supported in fixed position, and determines the angle of the skiving. The presser foot is shown in the form of a conical roll 6, mounted on an adjustable lever 8, 70 which is in turn mounted on a vertically adjustable slide 10, corresponding to the presser foot slide of the above patent.

In embodying the preferred form of the invention in this machine a moistening pad 75 carrier is arranged below the knife and in position to press a moistening pad against the surface of the knife at and back of its edge. The carrier shown is in the form of a trough 12, pivoted at one end to a bracket 14 and supported by a spring 16. The bracket may be conveniently secured in proper position with relation to the knife by screws 18 and 20, which engage opposite sides of a flange 22 on the machine 80 frame. The trough is so arranged that it underlies the knife edge and the upper edges of the trough are curved to correspond approximately to the curvature of the knife so that the rear side edge will lie close to 85 and conform approximately to the surface of the knife. The moistening pad 24 is carried in the trough and its upper surface conforms substantially to the outer surface 90 of the knife. The pad is pressed continuously against the surface of the knife by the action of the spring 16 and since the edge of the knife lies between the sides of the trough the pad also embraces the edge 95 of the knife to some extent and applies a film of moisture to the surface immediately within the edge, as well as to the outer surface for some distance back from the edge. The pad is preferably a sponge pad

since it has been found that sponge is not 100 only well suited for retaining a supply of moisture but that it also will apply the moisture to the knife in the form of a thin film and that it is also of such a character 105 that it will not be quickly rendered inef- 110

fective by continued contact with the rapidly rotating knife.

Water is supplied to the pad by a supply pipe 26, the mouth of which is preferably 5 plugged with sponge 28 so that the water may drip uniformly from the pipe onto the pad. The pipe may be provided with any suitable valve for regulating the supply of water thereto.

10 While it is preferred to employ the specific construction shown and described in applying the invention to the machine of the patent above referred to it would be understood that this construction and arrangement is not essential to the broader 15 features of the invention and may be varied or modified as found desirable or best suited to the construction of the machine in which the invention is to be embodied.

20 What is claimed is:

1. A skiving machine having, in combination, a tubular knife, a feed roll, a presser foot, a movable carrier for presenting a moistening pad to the edge and outer surface of the knife, and a spring acting on 25 the carrier to press a pad carried thereby against the periphery of the knife.

2. A skiving machine having, in combination, a tubular knife, a feed roll, a presser foot, a movable carrier, a sponge moistening 30 pad in the carrier, and a spring acting on the carrier to press the pad against the edge and periphery of the knife.

3. A skiving machine having, in combination, a tubular knife, a feed roll, a presser 35 foot, a movable carrier for presenting a moistening pad to the edge and outer surface of the knife, a spring acting on the carrier to press the pad against the edge and periphery of the knife, a pipe for delivering liquid onto the pad, and a sponge plug in the mouth of the pipe for securing 40 a uniform drip onto the pad.

4. A skiving machine having, in combination, a tubular knife, a feed roll, a presser 45 foot, a pivoted trough arranged to underlie the knife edge and having its upper edges curved to correspond approximately to the curvature of the knife, a moistening pad in the trough, and a spring supporting 50 the trough and pressing the pad against the surface of the knife at and back of its edge.

EUGENE J. RAY.
